[57] CLAIM

The ornamental design for a wine bottle stand, as shown and described.

DESCRIPTION

FIG. 1 is a perspective of the wine bottle stand of the present invention, where the neck of a wine bottle is inserted into the space between the cross-bar and side support members; the wine bottle stand being able to hold the wine bottle in a horizontal position when the stand is placed on a horizontal support surface.

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.
